UNITED STATES PATENT OFFICE.

MORRIS FALK, OF LEOMINSTER, MASSACHUSETTS.

PIN-TUMBLER LOCK.

1,414,348.

Specification of Letters Patent. Patented May 2, 1922.

Application filed March 10, 1921. Serial No. 451,138.

To all whom it may concern:

Be it known that I, MORRIS FALK, a citizen of the United States, residing at Leominster, in the county of Worcester and State of 5 Massachusetts, have invented a new and useful Pin-Tumbler Lock, of which the following is a specification.

This invention relates to a lock of the pin tumbler type. These locks have been regarded as safe heretofore but now instruments have been invented by which they can be picked very readily. The principle on which these instruments work is that the operator places a blade in the key-hole with 10 which he can force up the first pin and then turn the cylinder very slightly so as to get the hole in the cylinder slightly out of registration with the pin hole in the lock frame. This prevents the pin from dropping down, 15 at least temporarily. Then while holding the cylinder in that position he forces another blade in and carefully raises the second pin. The operation requires skill but it can be done so as to get both pins up where 20 they will be held from dropping down by the slight turn of the cylinder. He then works the other pins in the same way and by using one blade to hold the cylinder and a second one for manipulating the pin on 25 which he is working he succeeds in getting them all out of the way and is then free to turn the cylinder and release the door or the like which is held by it.

This invention is designed to prevent that 30 operation and it constitutes mainly the division of the cylinder into two parts independently rotatable and the removal of the surface on which the tools above mentioned have to rest in order to get the necessary 35 leverage.

Reference is to be had to the accompanying drawings in which

Fig. 1 is a side view of a pin tumbler lock constructed in accordance with this invention and shown partly in central longitudinal section;

Fig. 2 is a sectional view on the line 2—2 of Fig. 1;

Fig. 3 is a sectional view on the line 3—3 of Fig. 1, and

Fig. 4 is a bottom plan of the rear cylinder.

The lock is shown as provided with the usual front plate 10 and frame 11. These 50 are of the ordinary shape or can be made in any desired way. The frame 11 is pro-

vided with a number of holes or perforations 12 in an upstanding top part 13 for a corresponding number of locking pins 14. Each of the pins is held down by a spring 60 15 so as to naturally project into a hole 16 in the lock cylinder. The springs are held at the top by a slide 18 as usual. The cylinder is provided with the usual bar 19 which necessarily turns with it for operating the latches or other devices controlled 65 by the lock.

Except for a feature which will be described now, the cylinder and the other parts above described are of the usual ordinary 70 construction. The whole cylinder in which several pins engage is composed of two parts 20 and 21. These cylinders are located end to end in axial alignment but out of actual contact. The cylinder 20 is shown herein 75 as a little shorter than the cylinder 21 but that is not essential. They are located in the same passage in the frame 11 and are separated at their adjacent ends enough so that one cannot be turned frictionally by the 80 other.

It is to be noted that at the bottom of the rear cylinder 21 there is a longitudinal passage 23 communicating with the bottom of the key-hole 24. This is an important feature as will appear. 85

Also extending around each of the cylinders is a circumferential groove 25. This is for the reception of two ends 28 and 29 of a plate 26. This plate is fastened to the 90 frame 11 by a screw 27 and its integral ends are curved at their tops and project into the two grooves 25. Any other means may be employed for preventing longitudinal motion of the two cylinders 20 and 21 and thus 95 keeping them out of contact as well as preventing their displacement in any direction.

This lock is, of course, operated by the usual key in the usual way to turn the bar 19. If, however, any one attempts to pick 100 the lock by the instruments above mentioned he will encounter difficulty in the first place by the fact that his tools will find no surface on which to rest at the bottom of the key-hole. This is due to the presence of the 105 passage 23. Consequently, he cannot get the necessary leverage and will have much more than the usual difficulty in raising the first pin. But if he does succeed in raising that, and, in fact, in raising all the pins of the 110 first cylinder 20, he will then have this cylinder loose so that he can turn it around at

will. Now, however, he has lost his chance to hold the second cylinder 21 slightly out of the registering position shown in Fig. 3 while he raises the pins in that cylinder. Of course, the cylinder 20 being free to turn, cannot be used to apply pressure to hold the cylinder 21 out of position and he is confronted not only with this difficulty but by the fact that his tools cannot get any leverage at the bottom of the key-hole of the second cylinder. This prevents his picking this lock with the instruments above mentioned.

Although I have illustrated and described only a single form of the invention, I am aware of the fact that modifications can be made therein by any person skilled in the art without departing from the scope of the invention as expressed in the claims.

Therefore, I do not wish to be limited to all the details of construction herein shown and described but what I do claim is:—

1. In a pin tumbler lock, the combination of a pair of independently rotatable cylinders arranged end to end out of contact, each having pin holes for locking pins and having a circumferential groove, a frame provided with a corresponding number of spring pressed locking pins, and a plate having its ends projecting into said grooves for holding said cylinders independently against longitudinal motion.

2. In a pin tumbler lock, the combination of a pair of cylinders placed end to end, each of said cylinders having a row of holes for locking pins, a frame provided with a single row of locking pins, some for engagement in said holes in one cylinder, and the rest for engaging in the holes of the other cylinder, one of said cylinders having a longitudinal key-hole intersecting the row of pin holes and being provided with a longitudinal space extending under the key-hole whereby the bottom of the key-hole is left entirely open to prevent tampering with the pins entering the holes of the other cylinder.

3. In a pin tumbler lock, the combination of a frame having a cylindrical passage therein, a pair of cylinders located end to end in said passage, each having a row of holes for locking pins, and a row of spring pressed locking pins for engagement in said holes, each cylinder having a longitudinal key-hole intersecting the row of pin holes and the frame being provided with a longitudinal space extending under the key-hole in the rear cylinder only, whereby the bottom of the key-hole is left entirely open to prevent furnishing a base for use in tampering with the other cylinder.

In testimony whereof I have hereunto affixed my signature.

MORRIS FALK.
